[57] **CLAIM**

The ornamental design for body warming bag for a child's seat, as shown and described.

DESCRIPTION

FIG. 1 is a perspective view of a body warming bag for a child's seat showing my new design;

FIG. 2 is a front elevational view;

FIG. 3 is a top plan view;

FIG. 4 is a right side elevational view;

FIG. 5 is a rear elevational view;

FIG. 6 is a left side elevational view; and,

FIG. 7 is a bottom plan view thereof.

The broken line showing a child's seat in FIG. 1 is for environmental purposes only and forms no part of the claimed design.
